UNITED STATES PATENT OFFICE.

WARREN THOMAS NICHOLS, OF HEMPSTEAD, NEW YORK.

SUPPLY-VALVE.

SPECIFICATION forming part of Letters Patent No. 741,534, dated October 13, 1903.

Application filed March 30, 1903. Serial No. 150,215. (No model.)

To all whom it may concern:

Be it known that I, WARREN THOMAS NICHOLS, a citizen of the United States, and a resident of Hempstead, in the county of Nassau 5 and State of New York, have invented a new and Improved Supply-Valve, of which the following is a full, clear, and exact description.

The invention relates to water distribution, and its object is to provide a new and improved supply-valve, more especially designed for use in overhead tanks for water-closets and the like and arranged to prevent leakage by being normally held to its seat by the pressure-supply and to automatically 15 open against the said pressure-supply by the action of a float or similar device on the water falling below a predetermined level in the tank.

The invention consists of novel features and 20 parts and combinations of the same, as will be more fully described hereinafter and then pointed out in the claim.

A practical embodiment of the invention is represented in the accompanying drawings, 25 forming a part of this specification, in which similar characters of reference indicate corresponding parts in all the views.

Figure 1 is a longitudinal sectional elevation of the improvement as applied to a bottom supply-pipe of the tank. Fig. 2 is a side elevation of the improvement as applied to a top supply-pipe for the tank. Fig. 3 is an enlarged sectional side elevation of the improvement, and Fig. 4 is a sectional plan 35 view of the same on the line 4-4 of Fig. 3.

The valve-body A is provided with an entrance end A' and a discharge end A², and the said entrance end A' is screwed or otherwise secured to the head B' of a pipe B, 40 connected with a suitable pressure-supply. As shown in Fig. 1, the said pipe B is secured in the bottom of a tank C, into which the discharge end A² delivers the water, as herein-after more fully described, it being understood, however, that, if desired, the head B' and its pipe B may be attached to the top of the tank C, as shown in Fig. 2; but in either construction the improvements are alike, the only difference being that the valve-body, as 45 shown in Fig. 1, is vertically disposed and arranged in the lower portion of the tank, while, as shown in Fig. 5, the valve-body A

extends horizontally and is above the water-level of the tank C.

The entrance end A' of the valve-body A 55 is provided with a valve-seat A³, raised outwardly in the head B', and on the said seat A³ is adapted to be seated a valve D, normally held to the seat by the pressure-supply in the head B', so that leakage is not liable 60 to take place.

The valve D is adapted to open against the pressure-supply, and for this purpose the valve D is held on the fluted end of a valve-stem E, extending through the valve-seat A³ 65 into the body A to connect with a plug F, mounted to slide in a cylindrical extension A⁴, formed on the valve-body between the inlet and the outlet thereof, as plainly shown in the drawings.

On the outer end of the plug F is secured or formed an arm F', provided with an angular slot F², into which projects a pin G', held on a float-arm G, fulcrumed on the valve-body A and carrying the stem H' of a float 70 H, adapted to rise and to fall with the level 75 of the water in the tank C.

Now when the tank C is filled to a predetermined level, as shown in Figs. 1 and 2, then the valve D is held firmly to its seat A³, 80 and when the water passes out of the tank and the float H moves downward with the receding water-level then the arm G by its pin G' acts on the arm F' of the plug F, so as to move the latter inward in the extension 85 A⁴ and in doing so causes the stem E to move in a like direction to move the valve D off its seat A³ against the pressure of the water-supply. Now the water can pass from the head B' through the open valve-seat A³ 90 into the valve-body A and from the latter by the discharge end A² into the tank to refill the latter. Now as the water rises in the tank C the float H moves upward, and in doing so the arm G and pin G' act on the arm 95 F' of the plug F to move the latter outward, and with it the stem E and valve D, so that the latter readily passes to its seat A³ to again close the valve-body to the pressure-supply, the valve being held to its seat by the pressure of the water in the head B'.

In order to direct the flow of water through the body A to the discharge end A², I provide the interior of the valve-body with a de-

flector A⁵, extending under the extension A⁴, as plainly shown in Fig. 1.

The device is very simple and durable in construction, is not liable to easily get out of order, and by having the seat A³ raised in the manner described it is evident that the valve is firmly held to its seat when the tank is full, and consequently leakage and overflow of the tank are prevented, and at the same time the valve D moves readily off its seat when acted on by the float H, as previously explained.

Having thus described my invention, I claim as new and desire to secure by Letters 15 Patent—

In a supply-valve for tanks and the like, a valve-body having a raised valve-seat in its entrance end, and a cylindrical extension at its upper end, a valve of greater diameter 20 than the seat and adapted to be seated on the

valve-seat and held thereto by the pressure of the water-supply, a stem secured to the valve, a plug secured to the valve-stem and working in the cylindrical extension, said plug being provided with an angular and 25 slotted plate at its upper end, a yoke having its members pivoted at their ends to the cylindrical extension of the valve-body and provided with a pin extending between the members adjacent to their pivoted ends and working in the slot of the said angular plate, and a stem secured at its inner end to the said yoke and carrying a float at its outer end.

In testimony whereof I have signed my name to this specification in the presence of 35 two subscribing witnesses.

WARREN THOMAS NICHOLS.
